2,100,566

ROUTER

Oscar L. Munding, Glendale, Calif.

Application September 29, 1936, Serial No. 103,175

4 Claims. (Cl. 144—136)

This invention relates to and has for an object thereof, the provision of a router or like wood-working machine wherein an elongated cut such as a slot of predetermined dimension may be quickly and accurately formed in the work thru the medium of an efficacious manually controlled and power actuated means which effects such relative angular movement between the work and a rotary power operated cutting tool that said cut will be made in one continuous motor powered operation of the machine without requiring the exercise of any particular skill by the operator or necessitating his attention except for an initial manual starting of the machine.

15 A further important object of the invention is to provide certain new, novel and useful improvements in woodworking machinery of the router type, and embracing a woodworking tool of said character in which all of the operative parts are arranged compactly in a main supporting frame, with simple and improved driving or operating means, operating simultaneously in a vertical and horizontal manner or cutting direction.

Another characteristic of the invention is that 25 the machine is provided with propelling mechanism operating to automatically exert a bit forcing pressure thru the material worked upon simultaneously with the cutting operation.

Another characteristic of the invention is that 30 the machine is provided with propelling mechanism operating automatically to release both the bit forcing pressure and the bit cutting operation from contact with the material worked upon simultaneously with the completion of the cutting 35 of the material in a pre-determined manner.

A further characteristic of the invention, and 40 an important object thereof, is the provision of a woodworking router employing but one motor for the dual operation of the dual propelling mechanism.

And a further object of this invention is the provision of a reciprocating cutting mechanism making a clean cut through the woodstock, either 45 from the edge thereof, or centrally disposed therein, the invention in the latter feature being of great value particularly when used in connection with the manufacture of Venetian blinds for the cutting of the elongated slots in the multiple 50 number of slats comprising said class of window shades.

I attain these objects by the router comprising 55 my invention as disclosed by the appended drawing in which Figure 1 is a plan of typical cuts made by my router;

Figure 2 is an elevational view of my router, partly in section;

Figure 3 is an end view thereof partly in section;

Figure 4 is a section on the line 4—4 of Fig. 2, 5 and

Figure 5 is a section on the line 5—5 of Fig. 4.

Similar numerals indicate like parts throughout the several views, the woodworker's routing tool herein disclosed comprising a frame F supporting a table top T for supporting the material M during operation of the tool. The top T carries a guide G and is provided with an elongated aperture 1 thru which a cutting tool 2 operates; the same being operatively supported in a chuck 10 15 3 suitably carried by a shaft 4 of a motor 5. A suction fan 6 may be suitably secured to the shaft 4 for drawing the waste material produced during the cutting operation away from the tool, and said material may be readily disposed thru an 20 aperture 7 of a flexible tube 8 secured at one end to the underside of the table top T, and at the other to a suitable closure 9 carried by the housing of the motor 5. Said motor is secured by means of studs 10 to a slide plate 11 which is supported for a reciprocating movement horizontally 25 upon a guide plate 12 which is secured as by screws 13 to a slide plate 14 reciprocal vertically in a groove 15 formed in a bracket 16 attached by studs 17 to the frame F. 30

A slot 18 is formed in an offset end of the plate 11 to provide means for connecting one end of a connecting rod 19 to said plate as by means of a bolt 20 which also serves as an attaching means for one end of a rod 21 to said connecting rod 19, 35 the other end of said rod 21 being pivotally connected to a shelf 23 carried by the frame F.

A gear case 24 is suitably mounted upon the shelf 23, the reduction gears contained therein, but not shown being driven from a motor 25 by 40 means of pulleys 26, 27, 28, and 29, belts 30 and 31, and a shaft 32, said shaft being journaled in bearings 33 and 34 carried by the frame F.

A crank arm 35 is carried and driven by the shaft 32 and is connected to the plate 11 by means 45 of the connecting rod 19 and the stud 36.

A stud shaft 37 driven by the motor 25 thru the reduction gearing in the case 24 has keyed thereon a slide clutch member 38, the teeth 39 of which are disposed to engage teeth 40 of a 50 collar 41 formed on or suitably attached to a crank arm 42 loosely mounted upon the outer end of the shaft 37.

A connecting rod 43 is attached at one end by means of a stud 44 to the crank arm 42, and the 55

other end thereof is attached by means of a stud 45 to the plate 14. The clutch member 38 is shifted by means of a yoke 46 secured to a rocker shaft 47 journaled in a bearing 48 which is suitably secured to the shelf 23.

A lever 49 is keyed to an outer end of the shaft 47 and is connected as by means of a link 50 to a treadle 51. One end of the treadle is pivotably connected at 52 to the frame F and its other end is movably positioned within a guide slot 53 formed by the suitable attachment of a plate 54 to the frame F.

A spring 55 is provided having one end attached to the lever 49 and the other end attached 15 to the bracket 16.

The relative position of the several component parts as is herein disclosed forms but one of a number of ways in which the same may as readily be operatively installed, and in operation, the 20 woodstock to be worked upon is ordinarily manually held to the table top T for speed in operation, but may by suitable clamping means as readily be mechanically secured thereto.

With both the motors 5 and 25 in operation, 25 the treadle 51 is depressed under foot pressure, whereby the clutch member 38 is engaged with the collar 41 by means of the intervening link 50, lever 49 and yoke 46. The treadle is immediately thereafter released from the foot pressure, but 30 due to the inertia of the crank arm 42 and the parts thereto affixed, friction is set up between the meeting or engaged sides of the teeth 39 and 40 thereby preventing the separation of said teeth in connection with the action of the spring 55 35 until the crank arm 42 has reached the top dead center at which point gravity overcomes inertia, the spring 55 operates to restore the clutch out of engagement in inoperative or free position as shown by Fig. 2.

40 The one-half ($\frac{1}{2}$) revolution of the crank arm 42 just described drives the tool 2 upwardly thru the material M by reason of the motor 5 being gradually raised or rather forced upwardly thru operation of the connecting rod 43, stud 45, plate 45 14, screw 13, plate 12 and studs 10. Simultaneously with said upward movement of said motor 5, the cutting bit or tool 2 is forced against the woodstock material M or whatever be its character, and gradually therethru, the tool 2 being 50 rapidly rotated while in said upward movement by means of the motor shaft 4, and simultaneously therewith, a further or third, or reciprocating movement of said tool is effected in the following manner. The shaft 32 driven from the 55 motor 25 rotates the crank arm 35 to effect a horizontal reciprocation of the plate 11 by means of the stud 36, connecting rod 19 and stud 20, said operation in turn effecting a horizontal reciprocation of the motor 5 by reason of its attachment to said plate.

60 By means of the suitable reduction gears within the case 24 the ratio of revolutions between the crank arm 35 and the crank arm 42 may be approximately forty to one. It will therefore be understood that the reciprocation of the tool 2 within the slot 1 as seen in Fig. 1 is more rapid than the upward movement of said tool within said slot as seen in Fig. 2, the operation of said tool thus producing an elongated slot 56 within the material, and this regardless whether the cutting process is commenced at an edge of the stock or centrally disposed therein, a sample of each of said cuts being shown in Fig. 1. It is 65 also possible to sever the stock from edge to edge 70

should that be desirable or necessary for the lack of a saw.

As hereinbefore described, the pull of gravity upon the motor 5 and the respective parts connected thereto, acts to complete the last half of each revolution of the crank arm 42, wherefore it is necessary to exert pressure upon the foot treadle T for each separate cutting of an elongated slot to be produced in the material M, for although the tool continues to simultaneously rotate and reciprocate, it nevertheless is caused to move or rise upwardly only at the instigation of the operator by the depressing of said treadle.

The slot 18 is provided to permit the upward movement of the plate 11 simultaneously with the reciprocating movement of said plate. The rod 21 is arranged to prevent an upward movement of the end of the connecting rod 19 carrying the bolt 20, yet readily to permit the horizontal reciprocation of said rod 19 by means of the pivoted connection of the rod 21 to the bracket 22.

Readily manufactured in size as desired and proportionately built to perform the service it is resultingly expected to do, and from materials as readily procured in the open market, the tool is 25 extremely simple in construction, durable, positive in operation, and assures an even clean cut elongated slot, free from rough edges and burrs.

I am aware that slight modifications may from time to time be made in the details of structure 30 illustrated without departing, however, from the scope of the present invention, and as defined in the claims which are appended hereto. Hence, I do not limit my present invention to the exact description of construction herein disclosed, but 35 what I do claim is:—

1. In a machine of the character described, a frame, a work support thereon, a rotary cutting tool, a motor for rotating said tool, and power actuated means for moving said tool both horizontally and vertically against and relative to the work supported on said work support, said means including a continuously operating means for moving the tool horizontally and means manually controlled for effecting the vertical movement of the tool at will.

2. In a machine of the character described, a frame, a work table having a slot therein, a rotary upright cutting tool movable within and thru said slot for engagement with the work supported 50 on said table, a motor for rotating said tool, means for horizontally reciprocating said tool in said slot, a second motor, said motor providing a means for vertically reciprocating said tool during its rotary and horizontal movements, and a manually operable control means operable to initiate the starting of said vertical movement, said first named means including a continuously operated device connected with said second named motor, and said second named means including a manually operable means for establishing a drive connection with said last named motor.

3. In a machine of the character described, a frame, a work table thereon having a tool receiving opening therein, a vertically reciprocal member in said frame, a horizontally reciprocal carriage supported by said member, a rotary cutting tool supported by said carriage and being extensible thru and movable in said table opening, a 65 motor for rotating said tool, another motor, a drive connection between the second motor and said carriage, a drive connection between said second named motor and said vertically movable member, and manually operable clutch means for 70 75 75

controlling the last named drive connection for the operation of said tool.

4. In a machine of the character described, a reciprocating power driven tool simultaneously operating in a vertical and horizontal sequence to cut an elongated portion in material brought in contact therewith, means for driving said tool horizontally, and independent means for driving the same vertically, operation of said last named

means controlled independently of said first named means and at the instigation of the machine operator, means releasing said tool automatically from contact with said material worked upon, upon completion of the elongated cut-away portion in said material, and means for supporting the latter in operable contact with said tool, substantially as described.

OSCAR L. MUNDING.
